Primary Examiner — Jack Reickel*Assistant Examiner* — Bobby W Jones, II(74) *Attorney, Agent, or Firm* — Welsh Flaxman & Gitler LLC(57) **CLAIM**

The ornamental design for a UV sanitizing cabinet, as shown and described.

DESCRIPTION

FIG. 1 is a front perspective view of the UV sanitizing cabinet with the door closed;

FIG. 2 is a front view of the UV sanitizing cabinet shown in FIG. 1;

FIG. 3 is a rear view of the UV sanitizing cabinet shown in FIG. 1;

FIG. 4 is a top view of the UV sanitizing cabinet shown in FIG. 1;

FIG. 5 is a bottom view of the UV sanitizing cabinet shown in FIG. 1;

FIG. 6 is a left side elevation view of the UV sanitizing cabinet shown in FIG. 1;

FIG. 7 is a right side elevation view of the UV sanitizing cabinet shown in FIG. 1;

FIG. 8 is a front perspective view taken facing left of the UV sanitizing cabinet with the door open;

FIG. 9 is a front perspective view taken facing right of the UV sanitizing cabinet shown in FIG. 8;

FIG. 10 is a front perspective view taken from the bottom of the UV sanitizing cabinet shown in FIG. 8; and,

FIG. 11 is a front view of the UV sanitizing cabinet shown in FIG. 8.

The dashed broken line(s) define the bounds of the claimed design and form no part thereof.
